UNITED STATES PATENT OFFICE.

HAL S. WILLIAMS AND LYMAN G. WILSON, OF COLUMBIA, SOUTH CAROLINA.

RAILWAY-SIGNAL.

1,101,369.

Specification of Letters Patent. Patented June 23, 1914.

Application filed August 31, 1910. Serial No. 579,796.

To all whom it may concern:

Be it known that we, HAL S. WILLIAMS and LYMAN G. WILSON, citizens of the United States of America, residing at Columbia, in the county of Richland and State of South Carolina, have invented new and useful Improvements in Railway-Signals, of which the following is a specification.

This invention relates to railway signals and particularly to one designed to be automatically operated on destruction of any part of the track structure within a given radius of the signal, the object of the invention being to provide an electric circuit, a signaling device operating on closing of the circuit, relatively movable contacts in the circuit, and a fusible or destructible element which extends along a portion of the track structure and which is operatively connected with one of the contacts so as to hold it disengaged from the other contact to hold the circuit open.

A still further object of the invention is to provide a main signaling device and a supplemental signaling device both operating simultaneously on closing of the circuit, one of such devices being designed for use as a day signal while the other one is designed for use as a night signal.

In the drawings, forming a portion of this specification and in which like numerals of reference indicate similar parts in the several views: Figure 1 is an end view of our improved signal showing the same applied to a portion of a track structure. Fig. 2 is a top plan view thereof. Fig. 3 is a horizontal section taken on the line 3-3 of Fig. 1. Fig. 4 is a section taken on the line 4-4 of Fig. 3. Fig. 5 is a sectional elevation of the burner. Fig. 6 is a detail section through a portion of the wick tube showing the association of the igniter therewith. Fig. 7 is a detail section through a portion of the shaft casing, the shaft being shown in elevation. Fig. 8 is a detail diagrammatic view showing the contacts and the electrodes in the electric circuit. Fig. 9 is a detail top plan view of a portion of the track structure showing the application of a slightly modified form of our invention thereto. Fig. 10 is a section taken on the line 10-10 of Fig. 9. Fig. 11 is a detail section through one of the guide members. Fig. 12 is a similar view through a slightly modified form of guide member. Fig. 13 is

a section through the burner showing a slightly modified form thereof.

The signal as designed by us is of a structure which may be erected along the track structure at points a suitable distance from bridges or curves in the track structure or it may be arranged anywhere on the line. A hollow standard 1 extends upwardly from the base member 2. This base member is preferably mounted on the large tie A of the track structure B and located adjacent to one of the rails of the structure. The standard 1 is provided with a vertical shaft 3 whose lower end extends through the base 2, and as illustrated, a crank arm 4 is secured thereto. The crank arm 4 has secured thereto one end of a wire-like fusible or destructible element 5, the opposite end of the wire being secured to the track structure and preferably to one of the ties thereon. The said element 5 preferably extends between antifriction rollers 6 in the bearing member 7. This bearing member is located adjacent to one of the rails of the track structure, as clearly shown in Fig. 2 of the drawings. The purpose of the bearing member 7 and the antifriction rollers 6 is to permit the fusible wire 5 to move freely when it is partly mutilated or when it is burned between its fixed point and the bearing member. A spring 8 preferably of helical form has one end secured to the base 2, the opposite end of the spring is secured to the shaft 3 so that the spring will exert its tension to revolve the shaft on destruction of the element 5.

The standard 1 has fixed thereto at its upper end a casing 9 whose ends are formed with openings in which the lenses or transparent elements 10 are arranged. The casing 9 is so arranged with respect to the track structure that the lenses 10 are visible to the engineer on movement of the train in either direction.

An electric circuit is arranged in the casing 9 and in such circuit a pair of fixed contact arms 11 whose free ends 12 are arranged directly in the path of movement of the contact 13 on the upper end of the shaft 3. The wire 14 of the electric circuit connects one fixed contact 11 with one pole of the batteries D. These batteries are connected by the wire E with one binding post of the primary of an induction coil G. The opposite binding post of the primary of

said induction coil is connected by the wire I with one terminal of the battery J. The opposite terminal of the battery J is connected by the wire 15 to the other fixed contact 11. A main signaling device 16 consisting preferably of an oil lamp or the like is employed and as illustrated particularly in Fig. 3 of the drawings, it is disposed directly in line with the lenses 10. The burner 17 is provided with any well known form of wick tube 18 and immediately thereabove are arranged the electrodes 19 and 20 which are spaced sufficiently from each other so that through virtue of the induction coil when 15 the electric circuit is closed the spark will jump across the air gap at that point immediately above the wick of the burner to ignite the same. The electrode 20 is grounded on the burner. The electrode 19 extends 20 through the glass or like suitable well known insulated tube 21. As shown, this electrode is connected by the wire 22 with one terminal of the secondary of the induction coil, while a wire 23 has one end connected with 25 the burner, as shown in Fig. 3 of the drawings, and the free end thereof connected to the remaining terminal of the secondary winding of the induction coil. The auxiliary signaling device comprises a pivoted 30 arm 24 which is located on the standard 1 near the upper end thereof, this arm is connected at one end with a target 25. The arm 24 may be supported in a horizontal position by the pivotally connected links 26 and 27. 35 The link 27 is pivotally connected with the arm 24 and the link 26 is pivotally connected with the standard. The arm 24 is provided with a portion 28 which may be extended through the slot 29 in the casing 9 when it 40 is desired to hold the target immediately at one side of the casing. The portion 28 of the arm has formed thereon a pin 30 which is designed to be engaged by the hooked end 31 of a pivoted lever 33. The lever 33 is provided with a portion 34 which is disposed 45 in the path of movement of the trip member 35 on the shaft 3. This construction is such that simultaneously on closing of the electric circuit the trip member 35 will contact 50 with the portion 34 of the member 33 to move the hooked end 31 thereof to released position to permit the target arm to fall downwardly by gravity to an operative position.

55 In the modified form of our invention shown in Figs. 9 and 10, a crank arm 36 of the contact shaft is designed for engagement in the bell crank lever 37. This lever is mounted on the track structure and the arm 60 38 thereof extends over the said crank arm 36 and it is hooked, as shown at 39, to hold the crank arm against the tension of the spring on the contact shaft. The arm 40 of the bell crank lever is located directly in 65 line with the pivotally mounted trip member

41. This trip member is mounted on the track structure, and as illustrated, one terminal of the fusible element 42 is secured thereto. A spring 43 is fixed to the trip element 41 so as to move the same into engagement with the lever 37 immediately on destruction of the element 42. As shown in Fig. 9, two of such elements 41 are employed and the fusible elements are arranged so that one is disposed immediately at one side of 70 each rail of the track structure. This construction is preferable so that the fire in its movement in either direction across the track structure will destruct the flexible elements 75 causing a positive operation of the signaling 80 system.

As stated, the signaling system is designed to be operated on destruction of the track structure by fire but it is obvious that such apparatus as that described does not 85 rely particularly on the provision of fire to effect an operation of the system. It will be found equally as effective in cases of washouts or in any cases where destruction of the track structure would militate or destroy 90 that part of the signaling system which tends to hold the electric circuit open.

A brief illustration of the signaling system described herein and shown may be described as follows: Assuming the shaft 3 95 to be in a set position and held so by the fusible or destructible element which extends along sides of the track structure, the contacts 11 and 13 will be disengaged from each other. On destruction of the said fusible element the shaft 3 will be released therefrom and under tension of the spring 8 the shaft will be revolved to cause its contact to engage the contacts 11. At this time the circuit will be closed and, incident to the provision of the induction coil and the electrodes 19 and 20 of the lamp, the spark in its jump across the air gap above the wick tube will ignite the wick and the light will continue to burn uninterrupted. In some 100 cases it may be found desirable to open the primary circuit of the induction coil after the destruction of the fuse element. For this reason we employ a circuit breaker 44 which 105 preferably consists of a fuse wire 45 which extends directly over the wick tube of the burner 46 as shown in Fig. 13 of the drawings. The fuse element 45 has one of its ends connected with the post 47 of the burner. This post 47 is equipped with a 110 binding post 48, while a post 50, connected at one end to the free end of the fuse element 45, is grounded upon the burner, as is also a binding post 50'. When the circuit breaker is used, the wire E leading from the 115 battery D to the respective terminal of the primary winding of the induction coil is split intermediate its ends and the ends of the split portion connected to the binding posts 48 and 50' respectively. 120

125 130

In the modified form of the invention, the electrode 19' is substantially identical to that described in the preferred form and the wire 22 is connected to the induction coil as 5 previously described. The post 47 is insulated from the burner as shown at 52. In this form of the invention, it will be seen that when the circuit is closed, the current of the primary of the induction coil will 10 flow through the binding post 50', through the post 50, fuse wire 45, post 47 and then through the binding post 48 and remaining portion of wire E back to the battery. After 15 the wick of the burner has been ignited, the fuse element 45 of the burner will be destroyed and the primary circuit opened.

The system described and delineated herein is extremely simple and can be manufactured at a relatively low cost and when 20 once installed will be found efficient, durable and reliable for the purpose intended. In the form of bearing shown at 7' in Fig. 12 of the drawings, anti-friction rollers 6' are disposed vertically.

25 We claim:—

1. A signaling system including an electric circuit, a source of current therefor, a lamp, an igniter for said lamp arranged in the circuit, a gravity signal, means for holding said signal normally inoperative, a rotary shaft provided with means adapted to release said gravity signal, means carried by said shaft for closing the circuit to the igniter for lighting the lamp, a spring encircling said shaft for rotating the same, a crank connected to said shaft, and destructible track means connected to said crank to prevent movement of the shaft under the action of the spring.

40 2. A signaling system including an electric circuit, a source of current therefor, a lamp, an igniter arranged in the circuit and adapted to light the lamp, a gravity signal, means for retaining said signal in inoperative position, a rotary shaft, means carried by said shaft for closing the circuit to the igniter, means carried by the shaft for re-

leasing the signal holding means, a spring encircling said shaft for rotating the same whereby to release the signal and simultaneously close the circuit to the igniter, and destructible track means connected with said rotary shaft and holding the same normally against movement under the action of said spring.

50 3. A signaling system including a base, a hollow standard mounted upon the base, a casing fixed to the upper end of said standard, an electric circuit arranged within the casing, a source of current for the circuit, 60 a lamp positioned within the casing, and an igniter arranged in the circuit and adapted to light the lamp, a gravity signal, means carried by the casing for normally holding said gravity signal in an inoperative 65 position, a rotary shaft mounted in said hollow standard, means carried by the shaft and adapted to close the circuit to the igniter, means mounted on the shaft for releasing the signal holding means, means 70 for rotating said shaft to simultaneously light the lamp and release the gravity signal, and a destructible track signal connected with the last-named means to normally prevent movement of the shaft.

75 4. A signaling system for railways including a plurality of signals, a rotary shaft, means holding one of said signals in an inoperative position, means carried by said shaft and adapted to actuate the first means 80 to release said signal, means carried by said shaft and adapted to actuate the other of said signals simultaneously with the operation of the first signal, and a destructible element arranged upon the track structure 85 and normally holding said shaft against movement.

In testimony whereof we affix our signatures in presence of two witnesses.
